Primary Examiner — Mark A Goodwin(74) *Attorney, Agent, or Firm* — Merchant & Gould P.C.(57) **CLAIM**

The ornamental design for a boom hose apparatus, as shown and described.

DESCRIPTION

FIG. 1 is a front, top, left side perspective view of a boom hose apparatus showing our new design;

FIG. 2 is a front, top, right side perspective view of FIG. 1; FIG. 3 is a front, bottom, right side perspective view of FIG. 1;

FIG. 4 is a left side view of FIG. 1;

FIG. 5 is a right side view of FIG. 1;

FIG. 6 is a front side view of FIG. 1;

FIG. 7 is a rear side view of FIG. 1;

FIG. 8 is a top side view of FIG. 1; and,

FIG. 9 is a bottom side view of FIG. 1.

The broken lines in the Figures are for illustrative purposes only and form no part of the claimed design.
